ROLLING DOOR MECHANISM

Harry G. Kelly, Omaha, Nebr.

Application August 30, 1930. Serial No. 478,815

8 Claims. (Cl. 20—20)

The present invention relates to a door and hanging means therefor, and as employed in the present instance, it relates to a door adapted to be opened upwardly, closed downwardly, and moved laterally to be pressed tightly against the stops of a frame therefor as an incident to the closing of the door.

The objects of the present invention, among others, include the following:

- 10 An improved means for suspending a door;
 A novel means for moving a door laterally to the path of its normal movement to cause it to closely engage the stops of a frame therefor;
 A novel track for a sectional door;
 15 An unique arrangement of track, rollers, and deflectors to provide an improved door guiding and supporting device.

These, and such other objects of the invention as may hereinafter appear, are obtained by 20 the novel construction, unique arrangement, and improved combination of elements illustrated in the accompanying single sheet of drawing, disclosing one form of the invention, and in which

Figure 1 gives a perspective view of a door 25 and a hanging means therefor embodying one form of the present invention;

Figure 2 is an end elevation and section of the door and a supporting member therefor shown in Figure 1;

30 Figure 3 is a vertical fragmentary elevation with part of the track removed and showing the several rollers and deflectors at each side of the door;

Figure 4 is a transverse section through the 35 track illustrating one position of a roller and the track with a deflector for said roller therein and a recessed portion of said track opposite said deflector.

Figure 5 is a longitudinal cross section of the 40 track illustrating one position of a roller in contact with the inclined surface of a deflector and the parallel surface of a recessed portion of said track.

45 Figure 6 is a transverse section through a track illustrating one position of a roller in contact with the inclined surface of a deflector in a track having no recessed portions opposite said deflectors, said rollers being of a less diameter than the distance between opposed inner surfaces of the two track members.

50 Figure 7 is an elevation of a spring member which may be used with each of the roller brackets to maintain the contact of the rollers 55 with the inner face of the track opposed to the

door until said rollers contact with deflectors in said track.

Figure 8 is a section of the track with a spring member attached to said track at points not opposite the deflectors. 60

Like reference characters are used to designate similar parts in the drawing and in the description of the invention which follows:

The invention is adapted particularly for use in a garage structure. About a door opening 65 therein, generally of considerable width and designated 10, there are suitable frame members 11 which extend vertically along the sides of said opening 10, and a transverse frame member 12 which extends from one member 11 to 70 the other.

There may be several frame members 13 extending vertically upwardly from the member 12. Against the door opening 10, at the sides and top thereof there may be stop members 14 secured to the frame members 11 and 12 and having in a face 15 perpendicular to the face of frame members 11 and 12. 75

The stop members 14 on the opposite frames 11 are reversed and complementary, and the inner 80 face 15 may be placed parallel to and in registry with the edge of the side of door 16.

A vertical support member 17 is attached on either side of door opening 10 to the wall and to vertical member 11. A vertical section of 85 track 18 is secured to said support member, said track consisting of one track member 19 adjacent to support member 17 having a surface 20 parallel to the inner face of door 16 and a channel track member 21 having a flat surface 22 90 opposed to surface 20 of track member 19 and two wings 23 having opposed inner surfaces 24. Brackets 25 secure track member 21 to track member 19 and to support member 17 in exact 95 registry by means of fastening members 26 and 27.

Members 19 and 21 extend upwardly in parallelism until adjacent the upper portion of said door 16 when, in continued parallelism, said members are turned inwardly of the garage in 100 which used, forming a bent section 28, from which projects an approximately horizontal section 29, the extreme ends of which are supported approximately parallel to the garage ceiling by brackets 30 secured to the ceiling or roof of the 105 garage. Track members 19 and 21 are maintained in exact parallelism and registry in bent section 28 and horizontal section 29 by brackets 25.

In the channel 21, at spaced intervals, are de- 110

80

5 deflectors 31 having faces 32 inclined to surface 22 of said channel. Each of said deflectors has an edge 33 located at a certain distance from the wing of said channel outward from the edge of door 16 said distance being successively greater in each deflector encountered as the floor is approached.

85

10 Said deflectors are plainly illustrated in Figures 2, 3, 4, 5 and 6. The deflector nearest the top is designated 35, the one next there below, 36, and the next there below, 37, and that adjacent the lower end of channel 21 and near the floor of the garage, 38. Each deflector may be secured in the channel 21 in any suitable manner, as for example, by a plurality of screws 39, as disclosed in Figure 5. The deflector member 31 may be replaced by a tongue (not shown) cut from the body of track section 21 and bent inwardly of the track to present a surface disposed 15 similarly to deflector surface 32.

90

20 On a door 16, adapted to close opening 10, and comprising sections 40 which are transversely hinged together, there are a plurality of pairs of rollers at the opposite lateral edges thereof.

95

25 Section 40 at the top of the door 16 has a pair of brackets 41 with a section extending away from the face of the door. Such brackets 41 include a flanged base 42 attached to the door 16, relatively close to its top. The bracket 41 is of an L shape, one section being secured in base 42, and there being at the free end of the other section a shaft 43 upon which there is a roller 44. Said roller 44 is adapted to ride in the upper curved section 28 of the track when the door 16 is closed and as it is opened, to travel upwardly out of the curved section 28 into the horizontal section 29 thereof.

100

40 In the present disclosure, the door has four sections 40. Said sections are secured one to another by the hinges 45 which are suitably spaced apart.

105

45 At each end of section 40 where they are joined together, there is a hinge member 50 having opposed wings or straps 51, each one of which is secured to an opposed and adjacent section 40. Said hinges 50 include a pintle 52 which has an enlarged central portion 53 terminating in a roller shaft 54. On each shaft 54 is a roller 55 and in association therewith are a number of washers 56. At the end of the shaft 54 is a cotter pin 56a or the like, which is used 110 to maintain the roller 55 and the several washers in a selected arrangement on shaft 54.

115

50 The several members 50 are stationed as previously stated, at the intersection of sections 40 in door 16.

120

55 At the bottom of the door 16, there is another bracket 60 having a base 61. The bracket 60 terminates in a shaft 62 upon which a roller 63 and washers are held by a pin.

125

60 By reference to Figure 3, it will be noted that the rollers 55 and 63 and their associated washers are so arranged that the most highly positioned roller 55 is in alignment with roller 44, while rollers 55 between the second and third, and between the third and fourth, sections 40, and roller 63 are each mounted to ride upon their respective shafts in staggered arrangement. The rollers, as the bottom of door 16 is approached, each are one step nearer the edge of the door 16.

130

65 Each of the deflectors 35, 36, 37 and 38, as will be noted from Figure 3, is so positioned that only when the door 16 is about to be closed do the several rollers 55 and 63 register with the de-

135

150

8 deflectors provided therefor. Thus as the door 16 is raised, roller 63 disengages deflector 38, and conjointly the roller members 55 disengage themselves from deflectors 35, 36 and 37. In the further upward movement of the door 16, the deflectors 35, 36, and 37, do not interfere with the free movement of the door 16 for the rollers 55 and 63 can not contact with any of the deflectors except those provided for the engagement of each when the door is about to be closed. As the door 16 rises in its upward flight, it is guided primarily by the roller 44 at the extreme top of the door which engages the outward flanges of channel 21. The upper rollers 55 assist somewhat in preventing lateral displacement of the door 16. The roller 63 at the extreme bottom of the door 16 serves also to prevent such displacement as said rollers engage the internal flanges at the side of channel iron 21 adjacent to door opening 10. In this manner the door 16 is kept within limits by the roller members and track therefor which guide it effectively in its upward flight. Of course, in the downward flight, the channel 21 and rollers act in precisely the same manner.

5 during the upward travel of door 16 after said rollers disengage their respective deflectors and during the downward travel until said rollers engage said deflectors directs the travel of said door in a plane separated from contact with the stops 14 or frame inmembers 11 and 12. To permit the lateral displacement beyond the plane of surface 20 of track 19, recesses 81 wide enough to receive said roller are formed by bending outwardly sections of track 19 with a surface 82 parallel to the surface 32, of deflectors 31. Each of said recesses 81 is located in staggered relation with other recesses 81 and in exact position to receive one only of the rollers 55 and 63 as 10 each of said rollers comes in contact with its actuating deflector.

15 In Figure 6, rollers 55 and 63 are of a diameter considerably less than the distance separating the opposed surfaces 20 and 22. When said rollers 55 and 63 are forced by contact with their several actuating deflectors against the surface 20 of track number 19 the door 16 is forced against stop members 14 to assure a tight closure of opening 10. During the upward travel of 20 door 16 after said rollers 55 and 63 have become disengaged from their respective actuating deflectors, and during the downward travel of said door before the engagement of said rollers with said deflectors, the disengagement of said door from stops 14 is accomplished by the action of 25 springs 83 and 86 forcing said rollers into contact with surface 22 of track member 21 and away from surface 20 of track member 19.

30 Figure 7 shows one of such springs 83 having a circular portion 84 encircling the washers of all shafts bearing rollers 55 and 63, and free ends 85 in sliding contact with surface 20 of track members 19.

35 Another series of springs 86 may be attached at intervals to the vertical and curved surfaces 20 of track member 19, none being directly opposite the deflectors. Said springs 86 which are secured to track surface 20 contact with rollers 55 and 63 forcing said rollers to travel along surface 22 of track 21 except when said rollers are 40 in contact with their several actuating deflectors thus keeping the door 16 from frictional contact with face 15 of top member 14.

45 The pitch in the curve in the roller track heretofore referred to as curved section 28, is such that it will give to the upper section 40, when the door is closed, an outward thrust, to assure a tight contact with the stop 14 attached to frame member 12 which is arranged along the door opening for engaging the door 16 to complete an air and moisture tight closure of said opening 10.

50 Any suitable locking means may be arranged on the inside of the door 16 to secure the door in its closed position. In the present embodiment, said locking means are parallel rods 80 adapted to be moved laterally to engage the lower edge of each of two brackets 25 to prevent the lifting of the door when the rods 80 are in contact with such brackets 25.

55 The door 16 may have any desired counter-balancing or actuating system. In the present instance, this is a spring-actuated drum 90 upon brackets 91 attached to frame members 13. About said drum 90 is a cable 92 which is secured to the door 16 adjacent the bottom. This is but one form of counterweighting which may be employed. A cable, pulley and counter-balancing weights or a motor-operated drum might 60 supplant the counter-balancing system shown.

I claim:

1. A door, a channel track section and an opposed track surface at the sides of said door, rollers on the sides of said door in staggered arrangement, said rollers being enclosed between the parallel surfaces of said track sections, the opposed surfaces of said track sections being separated from each other a distance greater than the diameter of said rollers, and inclined deflector members on the inner surfaces of said track section opposite the surface of said door, said deflector members being arranged to deflect said rollers simultaneously at approximately the point at which said door becomes completely closed whereby said door when being closed is moved laterally. 80

15 2. The door described in claim 1, and in which there is associated with said rollers, a plurality of springs contacting the inner face of said track to force said door away from the track surface opposite said deflector members while said door is in motion. 85

20 3. Guide means for a door having staggeredly arranged side rollers, and comprising a channel iron member and an opposed track surface member in spaced relation, one of said members having a plurality of inclined surfaces in staggered arrangement to engage said side rollers simultaneously. 90

25 4. A door and support therefor comprising a channeled track having a plurality of spaced apart, inclined surfaces in staggered relation, a door having brackets extending into said channeled track, and rollers on said brackets arranged in staggered relation, the rollers adjacent the top and the bottom of said door being arranged to bear against opposite flanges of said channeled track. 100

30 5. Means for guiding a sliding door into an opening to be closed by said door comprising a relatively wide channel member having wings and a plurality of spaced apart, inclined sections in staggered arrangement, said door having a plurality of brackets extending across said channel member, rollers on said brackets, certain of said rollers engaging the opposite wings of said channel, and means on said brackets for arranging said rollers for simultaneous registry with said inclined sections of said track. 115

35 6. A frame, stops thereabout, a door having a plurality of paired shafts, all of said shafts extending laterally from said door, rollers on said shafts, in staggered relation, a track consisting of a channel portion and a portion providing an opposed track surface enclosing said rollers on each side of said frame, deflectors having inclined surfaces in staggered relation with each other associated with the track surface opposite said door and said track portion opposed to said deflectors having staggered recesses with associated inclined surfaces parallel to said deflecting surfaces in the opposite track portion, said recesses being adapted to receive a roller as each of said roller is simultaneously deflected by contact with a selected deflector from its plane of travel along said track at approximately the point of closing of said door, said door being thereby pressed against said stops on said frame. 120

40 7. In a vertically sliding door, rollers at the sides of said door, said rollers being in staggered relation, a track at each side of said door and having opposed surfaces between which said rollers travel, deflectors each having an inclined face in staggered relation in one of said surfaces, 125

and recessed sections in the opposite surface of said track, each of said recessed sections having an inclined face substantially parallel with the inclined face of an associated deflector, said rollers, deflectors and recesses being in complementary arrangement whereby to move said door as a unit transversely of its normal path of travel as an incident to said door attaining the end of its travel along said track.

10 8. A door, a channel track section and an opposed track surface at the sides of said door, rollers on the sides of said door in staggered arrangement, said rollers being enclosed between the parallel surfaces of said track sections, said 15 track sections being wider than the faces of said

rollers, the opposed surfaces of said track sections being separated from each other a distance greater than the diameter of said rollers, a bracket for each roller, spacing elements on said bracket, the position of the roller and spacer elements being interchangeable to admit of each roller riding over a selected longitudinal section of the track, and inclined deflector members on the inner surfaces of said track section opposite the surface of said door, said deflector members being arranged to deflect said rollers simultaneously at approximately the point at which said door becomes completely closed whereby said door when being closed is moved laterally.

HARRY G. KELLY.
